UNITED STATES PATENT OFFICE.

WILLIE L. DAUGHERTY, OF ORLANDO, FLORIDA.

GUARD-RAIL CHAIR.

1,381,454.

Specification of Letters Patent. Patented June 14, 1921.

Application filed November 17, 1920. Serial No. 424,709.

To all whom it may concern:

Be it known that I, WILLIE L. DAUGHERTY, a citizen of the United States, residing at Orlando, in the county of Orange and State 5 of Florida, have invented certain new and useful Improvements in Guard-Rail Chairs, of which the following is a specification.

This invention relates to improvements in guard-rail chairs, particularly upon the 10 subject-matter as embraced in my pending application, filed August 4, 1920, Serial No. 401,197.

The characteristic feature or point of difference of the present invention or improvement over my co-pending or companion case consists in providing the integral base member with an upstanding lug or portion upon the off side of the guard-rail, said upstanding portion or lug having an undercut 15 recess or slot intermediate the resultant shoulder formed in the lower part of said lug and the integral base member for the reception of the guard-rail flange. The base member is extended, as in my co-pending 20 case, to provide for the support of the track rail but is devoid of the opposite undercut recess or slot of said companion device, a stop without a slot being substituted therefor, said lug, however, having associated 25 therewith a tapering key insertible into a corresponding passage in said lug. Also in my present invention or improvement, I employ a clamp plate adapted, in connection 30 with said key, by subjecting the latter to a driving action to impart a clamping action 35 of said clamp plate upon the rail.

The invention, therefore, consists of the structural features and instrumentalities as above pointed out and defined in the appended claim.

The accompanying drawing illustrates the preferred embodiment of my invention, wherein it will be understood that various changes and modifications as relate to the 45 detailed construction and arrangement of parts without departing from the spirit or scope of my invention as covered by the claim, and in which drawing:—

Figure 1 is a plan view of railway rails 50 showing the application for use of my invention thereto.

Fig. 2 is a vertical section of the same.

Fig. 3 is a detached perspective view of my guard-rail chair.

Fig. 4 is a plan view thereof.

Fig. 5 is a detached perspective of the clamp plate.

In carrying out my present invention, I provide, as in my co-pending or companion case, a base member 1 and said base member with an upstanding lug 2, but, instead of forming said lug with a plurality of undercut slots, I provide said lug in the present instance with a single slot or recess 3 only, for receiving the base flange of the guard-rail, as clearly shown. Also, the upstanding lug 2, in my present improvement, has a passage or key-way 3^a extending entirely through said lug horizontally, said passage or key-way being tapered toward one end. 55 Also I provide in connection with said base member and its lug 2, a key 3^b of correspondingly tapered contour as said passage or key-way, the smaller end or terminal of said key projecting beyond said lug and provided with a transverse orifice 3^c adapted to receive preferably a cotter pin 4 to prevent the accidental displacement of said key. Further, I employ additionally a clamp plate 5 which is interposed or inserted 60 intermediate the lug 2 and the guard rail to coöperate with said key 3^b for effecting the clamping action of plate 5 upon the track rail. The clamp plate 5 is provided with lugs 5^a, one arranged at each of its upper 65 corner edges, the normal position thereof being vertical, to provide for the retention of said plate against accidental lateral or endwise displacement. It is to be understood that as a hammering or driving action 70 is delivered to said key, the pressure thus exerted upon the clamp-plate 5, will effectively secure the clamp-plate against the web of the guard-rail, as seen particularly 75 in Fig. 2, which will coöperate, with the contacting of the base of the guard-rail with that of the track-rail, to firmly seat or secure the guard-rail in place.

I claim and desire to secure by Letters Patent:

In a guard rail chair of the type described, a base-member having a stop-shoulder for the base of the track-rail, and an upstanding lug spaced off from said stop-shoulder and having an undercut recess receiving a 105 lateral edge of the base of the guard-rail, said upstanding lug also having a slot in its inner wall above the undercut recess, said

slot tapering longitudinally toward one end, a clamp having arms at its ends adapted to extend laterally of said upstanding lug and retain said clamp against longitudinal dis-
5 placement, and a key adapted to be received by the slot of said upstanding lug and tapering longitudinally to coöperate with the corresponding taper of said slot for wedg-

ing the key against said clamp and said clamp against the guard rail. 10

In testimony whereof I affix my signature in the presence of two witnesses.

WILLIE L. DAUGHTRY.
